UNITED STATES PATENT OFFICE.

CLIFFORD V. BATES, OF CHICAGO, ILLINOIS.

CIGAR-CUTTER.

1,119,220.

Specification of Letters Patent.

Patented Dec. 1, 1914.

Application filed March 16, 1914. Serial No. 824,945.

To all whom it may concern:

Be it known that I, CLIFFORD V. BATES, a citizen of the United States, residing at Chicago, county of Cook, and State of Illinois, have invented certain new and useful Improvements in Cigar-Cutters of which the following is a specification.

The principal object of my invention is to construct a cigar cutter, and primarily a pocket cigar cutter, which is both simple and positive in its operation.

A further object of the invention is to construct the device that slight pressure upon the cutting blade will throw the blade into operative position and at the completion of the cutting stroke the blade will be held within the casing.

Further objects of the invention are to construct a small device, the parts of which are durable and the cutting blade held in proper position at all times for making a clean cut on the end of a cigar without tearing or otherwise disturbing the wrapper.

With these objects in view my invention consists of the structure shown in the accompanying drawing in which—

Figure 1 is a plan view of my improved cigar cutter with the blade within the casing; Fig. 2 is a similar view to Fig. 1 with the blade in operative position ready for the cutting stroke. Fig. 3 is an enlarged view of Fig. 1 with the top of the casing removed; Fig. 4 is an enlarged cross-sectional view of Fig. 1; Fig. 5 is an enlarged longitudinal sectional view of Fig. 1; Fig. 6 is a rear elevational view of Fig. 3 with the rear wall of the casing removed.

Referring now more particularly to the drawing, the device comprises a casing 10 preferably formed in two sections which are secured together by any well known means, such as soldering at the joints. An opening 11 is formed through the two side walls of the casing. A guide plate 12 is mounted within the casing which is provided with a circular opening 13 in registration with the opening 11, and surrounding said opening is an annular flange 14 that is secured to the guide plate 12. The annular flange 14 is so designed as to extend into the opening 11 in one of the side walls of the casing. The guide plate 12 is provided with hinge members 15 and 16. A bar 17 provided with hinge members 18 and 19 similar to the hinge members 15 and 16, is secured between the

end walls of the casing by means of rivets 20. A hinge pin 21 extends through said hinges and in the preferred construction the hinge pin 21 is soldered to the hinge member 15 and to the hinge member 19 while the hinge pin is in a slightly twisted position so that the spring of the hinge pin normally tends to press the guide plate 12 against the upper wall of the casing. The cutting blade 22 is formed with a diagonally disposed cutting edge 23. One side of said blade 22 is extended beyond the cutting edge forming the flange 24 and a spring 25 is secured to the flange 24 and to the end 26 of the hinge pin 21 that projects beyond the hinge member 19. The other side of the blade 22 is extended beyond the cutting edge forming a spring arm 27, herein shown provided with a notch 28, the purpose of which will be hereinafter described. The blade is also provided with a neck 29 which slides between the end walls of the casing in the slot 30. The outer end of the neck 29 is provided with an enlarged end 31. A lug 32 is secured to the under side of the top wall of the casing and adapted to project into the notch 28 on the arm 27. A spring 33 is secured to the bottom wall of the casing to hold the blade 22 against the guide plate 12 and to also cause the spring arm 27 to be normally forced upward whereby the lug 32 will project into the notch 28 and thereby prevent the spring 25 from forcing the blade into open position when the blade is within the casing.

One edge 34 of the blade is doubled upon itself to form a flange which overlies one edge of the guide plate 12 whereby the blade will always be held in close contact with the guide plate 12.

The operation of the device is as follows: When the blade is in closed position the lug 32 projects within the notch 28 on the arm 27 thereby holding the blade within the casing and while the blade is so held the spring 25 is under tension. When it is desired to cut the end of a cigar, by inserting the end of the cigar in the opening 11 and against the blade 22 on the flange 14 and pressing slightly against either the flange or blade, the blade will move slightly toward the bottom wall of the casing depressing the spring 33 until the upper edge of the blade is below the lower edge of the lug 32, whereupon the spring 25 will force the blade outwardly

into the position shown in Fig. 2. The cigar end is then inserted within the opening 11 until it seats upon the flange 14 whereupon the blade is forced inwardly by 5 placing a finger upon the enlarged end 31 and the cutting edge 23 will sever the end of the cigar from the body thereof. At the completion of the cutting stroke the spring 33, as well as the hinge pin 21, forces the 10 arm 27 toward the top wall of the casing and when the notch 28 is brought into registering alinement with the lug 32 and the upper edge of the arm is forced above the lower edge of the lug 32 the blade will 15 again be held in its closed position and the device may be then inserted in the pocket of the user.

In addition to the spring 33 serving to hold the blade against the plate in order 20 that a close contact between the parts may be obtained and thereby better sever the cigar end, I have also provided a further means for accomplishing this result by making the hinge pin 21 serve as a spring 25 to normally force the guide plate toward the top of the casing, and as the guide-plate carries the cutting blade with it by reason of the flange 34, a close contact between the guide plate and blade is thereby procured. 30 The end wall of the casing may be also cut away, as shown at 35, so that any fragments of tobacco that may collect within the casing

will fall therefrom and not interfere with the working of the parts therein.

Having now described my invention, I 35 claim:

1. A cigar cutter comprising a casing having an opening therein, a cutting blade slidably mounted within said casing, a movable guide upon which said cutting blade 40 is slidably mounted, a spring normally forcing said cutting blade away from said casing and locking means between said blade and casing released by a lateral pressure 45 against said blade.

2. A cigar cutter comprising a casing having an opening therein, a guide within said casing, a cutting blade slidably connected to said guide, spring means for maintaining close contact between said cutting blade and guide, an opening in said guide in registering alinement with the opening in said casing, a spring for normally forcing said blade away from said casing and locking means between said blade and casing 50 released by lateral pressure against said blade. 55

In witness whereof I have hereunto subscribed my name this 14th day of March, 1914.

CLIFFORD V. BATES.
